UNITED STATES PATENT OFFICE

2,473,350

FOLDING PUSH CHAIR

Bernard Clarence Walter Spackman, Auckland,
Auckland, New ZealandApplication July 31, 1946, Serial No. 687,363
In New Zealand May 28, 1946

5 Claims. (Cl. 280—39)

1

The invention relates to folding push chairs, and has for its object the provision of an improved form thereof, capable of being operated by a person using one hand only, as in the case of a woman carrying a child on one arm, to be either folded into a compact and easily handled package, or to be unfolded and set up for use, both operations being easily and readily performed in a minimum of time.

According to the invention, the improved folding push chair comprises a seat portion; side portions hinged to the latter; wheels mounted on said side portions; a pivoted foot rest adapted to serve as a spreader between said hinged side portions, when the wheels are disposed for use; arm rests pivotally mounted on supporting bars pivoted to the seat portion, and adapted to fold thereon; a back consisting of hinged together portions, pivoted to said seat portion; spring catch means adapted to act between said arm rests and said back; and stops on said seat portion adapted with the spring catch means to hold the back, and the arm rests in position, when the chair is set up for use.

The invention is illustrated in the accompanying drawing, and will be more particularly described in conjunction therewith:

Figure 1 being a side elevation of the improved push chair opened out ready for use,

Figure 2 a sectional elevation, and

Figure 3 a front elevation of same;

Figure 4 a part cross sectional elevation, and

Figures 5, 6, 7 a side view, a front view and a rear view respectively, of the chair folded for carrying, transport or storage, as may be required.

The chair is formed with a hollow seat portion 1, provided with side and end walls, but no bottom, the side walls of said seat portion 1 each having hinged along its lower edge a hollow or double walled lower side 2, the hinges 3 being formed so that said lower sides 2 can be swung inwards and upwards into the hollow seat portion 1, but so that said lower sides are not able to be swung outwards beyond the vertical, in which position they form extensions of the side walls of the seat portion 1.

The wheels 4 upon which the chair is adapted to run along the ground or other surface, are mounted and accommodated in the hollow lower sides 2 by any approved means, and so as to project the necessary distance below the lower edges thereof to obtain a desired ground clearance.

A foot rest 5 pivotally mounted or hinged between lugs 6 one at each side of the lower edge

2

of the front wall of the seat portion 1, serves as a spreader and provides the means for maintaining the hinged lower side walls 2 apart, each in a vertical position, so that the wheels 4 are disposed for use, said foot rest 5 being formed with side walls, spaced apart and made rigid by a cross bar 7, containing an aperture 8, and with tongues or projections 9 on the inner ends of said spaced apart side walls, adapted to enter recesses 10 in the front ends of the lower side walls 2.

The back of the chair is in two portions, a lower portion 11 pivoted at the lower ends of its sides to the upper rear corners of the side walls of the seat portion 1, and an upper portion 12 hinged 15 to the upper edge of the lower portion 11, the joint 13 between said portions 11 and 12 being such that the latter is free to fold downwards on the former, but locks against said portion 11 and can not be moved upwards on same more than 20 is necessary to bring said portions 11 and 12 into alignment with each other.

The upper back portion 12 is provided with a handle 13, and contains an aperture 14, near the latter, and the opened out back formed by 25 the portions 11 and 12 being brought into line with each other is prevented from being raised above a predetermined position on the seat portion 1, by stops 15 on the outsides of the side walls of the latter, while said back is retained in the 30 raised position for use by spring catches 16 which snap into holes or recesses 17 in the arm rests 18 pivotally mounted on the upper ends of supporting bars 19, pivoted at their lower ends to the outsides of the side walls of the seat portion 1.

The rear supporting bars 19 of the arm rests 18 are, when the latter are raised into position for use, adapted to bear against the forward faces of the stops 15, and to be retained thereagainst by the spring catches 16 engaging in the 40 arm rests 18, so that the latter and the chair back are locked together, and are held against either forward or rearward movement by the stops 15.

The chair can be constructed or formed of any suitable material or combination of materials, 45 the arm rests 18 having an angle-iron cross section, while the back has a flange or web at each side through which the portions 11 and 12 are hinged together, and the portion 11 pivoted to the seat portion 1, but it is preferred to form the 50 chair of parts cast in or stamped out of plastic or similar material in order to facilitate mass production of the chairs.

To collapse or fold the chair, the spring catches 16 are disengaged from the holes or recesses 17, in the arm rests 18, which with the bars 19 are

folded down on the sides of the seat portion 1, with the arm rests 18 covering the bars 19, and resting on the upper side corners of the seat portion 1.

The chair is then gripped by the front end, and the foot rest 5 folded against the latter, which action withdraws the tongues 9 from the recesses 10 in the lower side walls 2, thereby leaving the latter free to swing inwards, following which the chair is turned upside down, to cause said lower side walls 2 with the wheels 4 thereon, to fold into the interior of the seat portion 1.

The partly folded chair is then tilted with the rear wall of the seat portion 1 uppermost, and the back consisting of the portions 11 and 12, folded over said rear wall, and the base of the seat portion 1, now with the side walls 2 and wheels 4 therein, so that the handle 13^a and the aperture 14 are disposed adjacent the aperture 8 in the cross bar 7 of the foot rest 5, whereby it is possible to grip both the handle 13 and cross bar 7 with one hand and conveniently carry the folded chair.

All of the aforesaid operations are capable of being performed with one hand, as for instance, when a child is being held on one arm, leaving only one hand free for folding the chair.

To open the chair for use, it is held right side up, and the handle 13^a released from the grasp, and by falling down, uncovers and releases the lower side walls 2, which drop to vertical positions and present the wheels 4 for use, following which the foot rest 5 is adjusted so that the tongues 9 enter the recesses 10, and keep said lower side walls 2 spread apart.

The chair is placed on the ground, the back raised into position, and the spring catches 16 engaged in the holes or recesses 17 in the arm rests 18; these operations also all being capable of being performed with one hand only.

What I do claim and desire to obtain by Letters Patent of the United States of America is:

1. A folding push chair comprising a seat portion, side portions hinged thereto and capable of being swung inwardly only, front and rear wheels mounted on said side portions, a pivoted foot rest adapted to serve as a spreader between said hinged side portions when all of the wheels are disposed for use, supporting bars pivoted to the seat portion, arm rests pivotally mounted on said supporting bars and adapted with the bars to fold on the seat portion, a back consisting of hinged together portions pivoted to said seat portion, the back being foldable partly around the seat portion to retain the hinged side portions with the wheels thereon and the pivoted foot rest in folded positions to provide with the foot rest means for carrying the folded chair, spring catch means adapted to act between said arm rests and said back, and stops on said seat portion cooperating with said spring catch means to hold the back and the arm rests in position when the chair is set up for use.

2. A folding push chair as claimed in claim 1 wherein the seat portion is formed with side and end walls and wherein the hinged side portions are hinged to the lower edges of the side walls and provide extensions of the side walls and are further provided with recesses, and tongues on the foot rest for engaging the recesses when the foot rest is moved to position to hold the side portions with the wheels thereon extended.

3. A folding push chair comprising a hollow seat portion having depending side and end walls, side portions hinged to the lower edges of said side walls and provided with recesses at their front edges and capable of being swung inwards only, front and rear wheels mounted on the inner surfaces of the hinged side portions, a foot rest pivoted to the lower part of the front end wall of the seat and including side walls with tongues thereon capable when the foot rest is swung downwardly of being engaged in the recesses in the hinged side portions to maintain the same spread apart and the wheels disposed for use, a back consisting of hinged together portions adapted to lock against movement in one direction when brought into alignment with each other, the outer back portion constituting a handle having an aperture, bars pivoted to the seat portion, and an arm rest pivotally mounted on the bars, stops on said seat portion between the bars and said back, and spring catches adapted to engage in the arm rest and to maintain the latter and said back against said stops when the chair is set up for use.

4. A folding push chair as claimed in claim 3 in which a cross bar is carried by the side walls of the foot rest and is provided with an aperture which cooperates and aligns with the aperture in the outer back portion when the chair is folded to form hand holds to facilitate the carrying thereof.

5. A device as claimed in claim 3 in which the outer edge of the foot rest is curved upwardly and when in a folded position is adapted to engage the front edges of the arm rests to hold the latter against the seat.

BERNARD CLARENCE
WALTER SPACKMAN.
